UNITED STATES PATENT OFFICE.

EDGAR HERBERT GRANT, OF MARSHALL, MICHIGAN.

DESIGN FOR A FOLDING CABINET.

SPECIFICATION forming part of Design No. 25,783, dated July 14, 1896.

Application filed May 27, 1896. Serial No. 593,351. Term of patent 31 years.

To all whom it may concern:

Be it known that I, EDGAR HERBERT GRANT, a citizen of the United States, residing at Marshall, in the county of Calhoun and State 5 of Michigan, have invented a certain new and useful Design for Folding Cabinets; and I do declare the following to be a full, clear, and exact description of the invention, such as will enable others skilled in the art to which it 10 appertains to make and use the same, reference being had to the accompanying drawing, which forms a part of this specification.

My invention relates to a certain new and useful design for cabinets and especially to 15 that class of furniture articles comprising a folding washstand and rack or cabinet.

My design is clearly illustrated in the accompanying drawing, in which I have shown a perspective view of a cabinet embodying 20 my design.

The design consists, essentially, of an upright portion substantially rectangular in outline, having the lower ends of the sides

thereof scalloped, with the front edge of the vertical side of the cabinet outwardly flaring 25 near its lower end, thence continued upward in a straight line and parallel with the back side of the cabinet, and at a location below the middle of the cabinet the said edge is outwardly curved, thence continued upward in 30 a straight line to the molding about the top of the cabinet.

The front face of the cabinet is made up of three panels substantially square, with a wainscoting between the two upper panels. 35

What I claim to be new, and desire, to secure by Letters Patent, is—

The design for a folding cabinet substantially as shown and described.

In testimony whereof I affix my signature 40 in presence of two witnesses.

EDGAR HERBERT GRANT.
